TOY VEHICLE

Sidney Godell, Chicago, Ill., assignor to Arvey Corporation, Chicago, Ill., a corporation of Illinois

Application May 17, 1943, Serial No. 487,206

5 Claims. (Cl. 46—218)

This invention relates to improvements in toys, and particularly structural toys formed of cardboard, paperboard and the like sheet material.

More specifically my invention relates to novel articulation or coupling means for toy trains, cars, wagons and the like vehicles, formed principally of cardboard, whereby the cars or units of such trains may be securely coupled by means which permit pivotal or angular movement of the units relative to each other.

Other objects and advantages of my invention, including details of construction and arrangement of parts will be apparent from a consideration of the following specification and drawing, wherein:

Fig. 1 is a diagrammatic plan view of a plurality of toy railroad cars coupled together, in accordance with my invention.

Fig. 2 is a fragmentary, sectional plan view illustrating the end portion of two adjacent cars articulated by my novel coupling means.

Fig. 3 is a view similar to that of Fig. 2, but with one of the cars in coupled angular relationship to the other.

Fig. 4 is a fragmentary sectional elevation of two toy cars in coupled relationship.

Fig. 5 is a fragmentary sectional plan view of the end of one form of car illustrating a coupling link engagement aperture.

Fig. 6 is a view similar to that of Fig. 5 illustrating another form of car construction and the position of its engagement aperture.

Fig. 7 is a section on the line 7—7 of Fig. 4.

Fig. 8 is a plan view of my novel coupling link.

Referring to the drawing, Fig. 1 illustrates a plurality of toy railroad cars formed of cardboard in articulated engagement by means of my novel construction and coupling links showing the angular flexibility of one car with respect to another, car A simulating a streamlined locomotive, car B a passenger or baggage car, and car C an observation car. It will, of course, be understood that any number of cars of any simulated form may be coupled by providing them with suitable apertures and coupling links hereinafter more fully described.

My coupling links comprise a strip or shank portion 10, which may or may not be provided with the illustrated intermediate bulge, each end of the strip terminating in a laterally projecting tab 11, the tabs preferably merging with the shank by means of the tapered portions 12 and defined from the shank thereat by means of the score lines 13.

For reception of the coupling links, the base or

floor portion of the toy car body is provided with a suitable aperture adjacent one or both ends, and adjacent the car end wall. One form of car construction, as far as is pertinent to the present invention, is illustrated by the car A of Fig. 5. This car comprises a base 14 and an end wall 15 spaced from the end of the floor or base 14, to provide a platform. This platform is formed with an elongated slot or aperture 16, preferably as illustrated in the outline of an isosceles trapezoid, the bases thereof being parallel to the edge of the car floor 14, with the shorter base adjacent to the floor end. The length of the longer base of the trapezoid is slightly less than the width of a tab 11, but the length of the shorter base is greater than the width of the straight strip portion 10. The greatest oblique dimension of a tab from one end of the score line 13 to an opposed outer corner of the portion 11 is preferably substantially equal to the greatest opening of the apertures. The length of each tab 11 from the score line 13 to the outermost edge is greater than the altitude of the trapezoidal aperture, or equivalent dimension of an otherwise shaped slot, such as for example a rectangular slot or one with arcuate ends, not illustrated, and not fully equivalent.

Another form of toy car construction is that illustrated by the car B of Fig. 6. Here the end wall 17 rises from the edge of the floor 18, their conjugation being defined by the line of fold 19. The floor 18 is provided with a suitable slot or trapezoidal aperture 20, similar to aperture 16. One side of the slot or the short base of aperture 20 terminates preferably as illustrated at the fold line 19 and is defined by the lower edge of the end wall 17.

It will be understood, however, that the aperture 20 may be spaced inwardly of the fold line 19 similar to the endwise spacing of aperture 16, the sole difference between the use of the apertures 16 and 20 being that in the former a tab 11 may be inserted either upwardly or downwardly, whereas in the latter a tab may be inserted only upwardly because downward ingress is blocked by the end wall 17. The operative function of the two forms is, however, substantially the same and with like effect, and each may be engaged by either of the two tabs 11 on a strip 10.

For the purpose of illustration, Figs. 2, 3 and 4 show a car of type A coupled to a car of type B, a tab 11 being inserted upwardly through the aperture 20 of car B in the only possible manner, and a tab 11 inserted downwardly through the

aperture 16 of car A, but in this instance, although not illustrated, the tab could have been inserted upwardly with like function and effect.

As previously indicated, the width of the tabs 11 are preferably slightly greater than the widest portion of the slots or apertures 16 and 20, and the greatest oblique dimension of the tabs from their inception at the score lines 13 are preferably substantially equivalent to the greatest opening of the slots or apertures. However, since both the car bodies and the coupling links are of cardboard or similar paperboard, the tabs may be extended through the apertures by slight urging, or if necessary slight deformation, or by means of or with the aid of angularly inserting a tab through a slot with one corner of the tab forwardly. Either before or after insertion the tabs 11 are bent on the score lines 13, either downwardly when a tab is inserted downwardly, or upwardly when a tab is inserted upwardly, so as to permit the intermediate coupling strip portion 10 to lie substantially parallel to the floors of two adjacent coupled cars, as best illustrated in Fig. 4, with the tabs inclined thereto.

After coupling two cars in the manner and by the means described, uncoupling by relative movement, either linear or angular, is prevented by reason of wedged frictional engagement of the parts or abutment of the lateral tab projections against the surfaces defining the slots or apertures, or wedging of their tapered roots of the tabs against the inclined sides defining the trapezoids, or abutment of the progressively greater width of the tabs against the progressively narrower width of the apertures when two coupled cars are in relative tension, together with the limitation of the defining edge of the shorter base of the apertures. Limited angular movement of one car with respect to another, while in coupled engagement is however permitted, as partially illustrated in Fig. 3, by reason of the fact that the coupling strip portion 10 at its conjugation with a tab 11 is appreciably narrower than the shorter base of the apertures 16 and 20, and thus permits pivotal movement even when two cars are in tension about one of the lateral projections of a tab 11 or its adjacent inclined root 12, although angular withdrawal of a tab from an aperture in such position is likewise limited by reason of the relatively greater width of the tab with respect to the aperture.

It will thus be evident that my foregoing described and illustrated invention provides an efficient and effective flexible coupling means for toy cars or trains which may be formed of paperboard without the requirement of metallic links, pins and the like.

I claim as my invention:

1. Coupling means for toy vehicles of the class described comprising a vehicle base formed with an aperture adjacent an end thereof and a coupling link adapted to be engaged thereby, said coupling link comprising a shank portion of lesser

width than said aperture and a contiguous laterally projecting end tab portion the greatest dimension thereof being at least equal to the greatest dimension of said aperture and adapted to be forcibly urged therethrough.

2. Coupling means for toy vehicles of the class described comprising a vehicle base formed with an elongated aperture extending parallel to and adjacent an end thereof and a coupling link having a shank portion of lesser width than said aperture terminating in an end tab formed with laterally projecting portions, said tab being of greater width than said aperture and being adapted to be inserted therethrough by partial distortion.

3. Means for coupling two adjacent ends of toy vehicles of the class described, each of said vehicles comprising a bottom formed with an elongated aperture extending parallel to and adjacent an end thereof and a coupling link comprising two opposed end tabs of greater width than said apertures and with a greatest dimension substantially equal to the greatest dimension of the apertures and adapted to be forcibly inserted therethrough into locking engagement, said tabs being connected through a strip having portions contiguous with said tabs of lesser width than said apertures, and defined from the tabs by surface score lines.

4. Means for flexibly coupling the ends of two adjacent paperboard trains and the like toy vehicles, each of said vehicles comprising a bottom formed with a trapezoidal aperture extending parallel to and adjacent an end thereof, the inclined sides defining said trapezoid converging toward said end, and a coupling link comprising two opposed end tabs of at least equivalent width to the largest width of said apertures and adapted to be urged therethrough, said tabs being connected through a strip having portions contiguous with said tabs of lesser width than the shorter base of said apertures.

5. Means for flexibly coupling the ends of two adjacent paperboard trains and the like toy vehicles, each of said vehicles comprising a bottom formed with a trapezoidal aperture extending parallel to and adjacent an end thereof, the inclined sides defining said trapezoid converging toward said end, and a coupling link comprising two opposed end tabs adapted to be inserted therethrough and of slightly greater width than the largest width of said apertures and having tapered root portions converging toward a connecting strip having portions contiguous with said tab roots of lesser width than the shorter base of said apertures and defined from the root of the tabs by surface score lines and foldable thereto to permit said connecting strip to lie substantially parallel to said vehicle bottoms with said tabs inclined thereto.

SIDNEY GODELL.
